UNITED STATES PATENT OFFICE.

WILLIAM J. ROBERTS, OF PAWTUCKET, RHODE ISLAND.

LOOM-SHUTTLE.

1,259,294.

Specification of Letters Patent. Patented Mar. 12, 1918.

Application filed June 7, 1917. Serial No. 173,340.

To all whom it may concern:

Be it known that I, WILLIAM J. ROBERTS, a citizen of the United States, residing at Pawtucket, in the county of Providence and

5 State of Rhode Island, have invented certain new and useful Improvements in Loom-Shuttles; and I do declare the following to be a full, clear, and exact description of the invention, such as will enable others skilled 10 in the art to which it appertains to make and use the same.

This invention relates to new and useful improvements in loom shuttles, more particularly to the formation of the thread delivery eye thereof.

The principal object of the invention is to provide a strong yet simply constructed thread delivery eye which may be inexpensively manufactured, yet which will be very 20 efficient in operation and easily threaded.

An additional object is to provide a loom shuttle eye which is so constructed that the thread will be prevented from "ballooning," or otherwise leaving the shuttle when it is 25 slack.

With these and other objects in view, the invention resides in the novel features of construction, combination and arrangement of parts which will be hereinafter more particularly described and claimed, and shown 30 in the drawings wherein,

Figure 1 is a plan view of the delivery end of an ordinary form of loom shuttle showing my improved eye disposed therein;

35 Fig. 2 is a side elevation of the parts shown in Fig. 1;

Fig. 3 is a vertical transverse section taken on the plane of the line 3—3 of Fig. 1;

Fig. 4 is a detail side elevation of the delivery eye removed from the shuttle, the parts thereof being separated;

Figs. 5 and 6 are respectively end elevations of the body and cap members of the improved eye shown in the preceding figures.

45 Fig. 7 is a plan view of a slightly modified form of my invention;

Fig. 8 is a side elevation of the parts shown in Fig. 7;

50 Fig. 9 is a vertical transverse section on the line 9—9 of Fig. 7;

Fig. 10 is a disassembled side elevation of the eye illustrated in Figs. 7, 8 and 9;

Fig. 11 is an end elevation of the body member of this eye and Fig. 12 is a similar 55 view of the cap member.

Referring more particularly to the several figures of the accompanying drawings, it will be noted that although the invention may be constructed in several slightly different forms, each operates in substantially the same manner and is very similar in general formation. Similar reference characters indicate like parts in the several figures illustrating each form.

60 In carrying out my invention as shown in Figs. 1 to 6, the shuttle S is provided with a transverse opening 1 to receive the two-part thread guide or shuttle eye 2. It will be noted from Fig. 3 that the opening 1 is shouldered intermediate its ends as at 3, and adjacent one end as shown at 4, thereby gradually decreasing the diameter of the opening from one side to the other of the shuttle. After the delivery eye 2 has been 70 placed in the opening, the end in which it is inserted is closed by a plug 5 held in place by any preferred means such as the pin 6; the other end of the opening designated by the numeral 7 forms the outlet for 75 the thread which is wound upon the cop C disposed within the bobbin chamber B.

80 The two part delivery eye 2 comprises a body member 8 and a cap member 9, the former having one end cylindrically reduced 85 as at 10 to be disposed in that portion of the opening 1 positioned between the shoulders 3 and 4. Since one end portion of this body member is smaller than the other an annular shoulder is necessarily formed 90 which is adapted to rest upon the annular shoulder 3 of the shuttle. The outer end of the reduced portion 10 of the body member abuts the annular shoulder 4. This body member has an axial bore 11 which extends 95 throughout its length and communicates with the opening 7 in one wall of the shuttle. Also formed in the body member is a helical slit 12, the same extending through the wall thereof and into communication with the 100 bore 11. Adjacent one side of slit 12 the body member 10 is reduced as shown at 12^a, in order that the thread may pass between said body member and the wall of the opening in which it is positioned.

105 The cap member 9 forms the second por-

tion of the delivery eye, this part consisting of a relatively flat disk of a diameter similar to that of the largest portion of the body member and adapted to engage the outer end 5 of this portion. This part of the body member has one side cut away as illustrated in the several figures of the drawings to form a shoulder 14, this cut away portion being extended from substantially the center of the 10 body member outwardly. The body member 8 is similarly shouldered as shown at 15, but on the opposite side thereof from the cut away portion 14. Also, the shoulder 15 is only approximately one-half the width 15 of the shoulder 14, so that when the cap member is placed in engagement with the enlarged part of the body member, there will be a channel-shaped passageway formed therebetween which communicates with both 20 the inner end of the bore 11 and the slit 12. This passageway first receives the thread T from the cap during the threading of the eye.

It will be noted that this channel-shaped 25 passageway extends transversely through the delivery eye and at right angles to the axis of the bore 11. One wall of the passageway, preferably that formed by the end of the body member, is provided with a longitudinally extending groove 16, while the 30 opposite wall has an inwardly curved lip 17 formed integrally therewith, the curved end of said lip being in close proximity to the bottom of the groove 16 so as to form a con- 35 tracted space therebetween. This lip is of a length slightly less than one-half the width of the large portion of the body member, or the diameter of the disk which forms the cap member; the lip is disposed 40 to one side of the longitudinal axis of the delivery eye, preferably being disposed toward the bobbin recess B as shown in dotted lines in Fig 1. The inner face of the lip is longitudinally grooved as at 18 and the opposite sides thereof are notched as at 19.

The purpose of this grooved lip 17 is to 45 guide the thread into the passageway between the two parts of the eye, said thread being delivered into engagement with the grooved part of this lip through a vertical 50 thread slit 20, as is usually provided in the shuttle S, said slit extending from the bobbin recess to a point adjacent the delivery end of the shuttle, from whence it turns di- 55 agonally backward and downwardly as shown at 21, said slit continuing until it intersects the opening 7. As is usual in de- 60 vices of this character, the thread slit extends into the body of the shuttle and com- 65 municates with the various passageways of the delivery eye. In the present case the thread T after being drawn from the supply in the bobbin chamber and placed in that portion of the slit designated by the numeral 20, is drawn inwardly by the curved portion

of the lip 17 until it is in the passageway between the two parts 9 and 10 of the eye. With continued pull on the thread until it rests in the portion 21 of the thread slit, the same will be guided by the helical slit 12 70 into the axial bore 11, from which it extends out through the opening 7.

The shuttle, after the thread has been thus disposed, is ready for operation, said thread then running directly from the bobbin chamber into the passageway between the two parts of the eye and into the axial bore 11. The thread during its movement through these parts will engage the inner grooved 75 face 18 of the curved lip 17, and the inner 80 and outer edges of the bore 11, therefore these points of contact are preferably formed of porcelain or other vitreous material. The whole of both parts may be either formed of vitreous material, or of metal with the ex- 85 ception of the points of contact of the thread, which include those mentioned above as well as the bottom of the groove 16, the curved outer face of the lip 17, and the upper end 90 of the slit 12.

This type of shuttle eye is adapted to be automatically threaded by the operation of the shuttle within the loom, but that form illustrated in Figs. 7 to 12 is adapted particularly for hand threading. The shuttle 95 eye illustrated in the last mentioned series of figures is very similar to the first described form, the chief point of difference being in the size of the delivery eye and the hole or opening in the shuttle in which it is disposed. 100

From Fig. 9 it will be noted that the opening 25 is of substantially the same diameter throughout its length and extends from one side to a point adjacent the opposite side of the shuttle and an outlet opening 26 of 105 smaller diameter in this side of the shuttle communicates with the opening 25. Thus only one shoulder is formed against which the delivery end of the two part delivery eye 27 engages, the other end having a plug 110 28 abutting the same, the latter serving the same purpose as the plug 5 above mentioned. In this form both the body member 29 and the cap member 30 are substantially the same diameter, otherwise the parts are very similar 115 and correspond to like parts in the eye 2.

As shown in Figs. 7 and 8, the thread slit of the shuttle S' is somewhat different from the slit of the shuttle S, although its bottom 120 communicates with the several passageways in the delivery eye 27 and is used for the same purpose as that first described. The thread slit of the shuttle S' extends from the bobbin recess B' to a point 31 adjacent the outer side of the opening 25 where it 125 makes a rather abrupt turn as shown at 32, this portion 32 of the slit extending around the shuttle until it communicates with a similar slit 33 formed in the longitudinal plane 130 of the shuttle and opening into the outlet

opening 26. The thread passes through the several parts of this thread slit into the delivery eye in the manner above described.

It will be readily noted that since no portion of these delivery eyes are exposed to direct contact with any hard or metallic surface, the same may be readily formed of a vitreous material without danger of their being broken, the wood of the body of the 10 shuttle and the plugs 5 and 28 forming cushioning members therefor. Various minor changes may be made in the form and proportion of the device other than that shown in Figs. 7 to 12, without departing from the 15 principles of the invention or sacrificing any of the efficiency of the device.

I claim:—

1. A two-part delivery eye for loom shuttles comprising a body member having 20 an axial hole extending throughout its length, one end of said member being shouldered, the wall of said member having a curved slit communicating with said hole, a cap member resting on the shouldered end 25 of the body member, the space between the cap and said end of the body member forming a thread receiving channel, and a curved lip extending into said channel to guide a thread thereinto.

30 2. A shuttle of the class described pro-

vided with a bobbin chamber having a thread slit extending therefrom, said slit communicating with a delivery eye, the latter comprising a body member having an axial bore extended throughout its length, 35 one end of said member being shouldered, the wall of said member having a curved slit communicating with said bore, a cap member resting on the shouldered end of the body member, the space between the cap and 40 said end of the body member forming a thread receiving channel, and a curved lip extending into said channel to guide the thread from said thread slit into said channel, said thread being guided from said channel to the 45 axial hole by said curved slit in the wall of said body member.

3. A structure as specified in claim 1, said cap member having at its inner end a shoulder contacting with the shoulder of said 50 body member, whereby relative rotation of the two is prevented.

In testimony whereof I have hereunto set my hand in the presence of two subscribing witnesses.

WILLIAM J. ROBERTS.
